[57] ABSTRACT

[51] Int. Cl. H03h 7/30, G02f 1/28

A folded path acoustic device of a homogeneous solid material in which an acoustic signal is folded in a non-overlapping path used as a processor or delay line. The acoustic signal is reflected from facets of the body in a planar path in a manner to avoid mode conversion. The acoustic signal can also be folded from one planar path to another in a three-dimensional configuration of the delay line.

FOLDED PATH ACOUSTIC DELAY LINE AND OPTICAL PROCESSOR

BACKGROUND OF THE INVENTION

1. Field of the Invention

This invention relates to solid ultrasonic delay lines in general. More particularly, it applies to optoacoustic processors wherein it is necessary to process signals of long duration in an optical system.

2. Description of The Prior Art

It has been the general practice to construct multi-facet delay lines using essentially a polygonal shaped device. Usually the signal is introduced by means of a transducer and undergoes a series of reflections from the multiple sides of the delay line until finally it is extracted from the delay line by a second transducer or absorbed by some absorption medium. However, segments of the path of the acoustic signal in such a device generally overlap with other segments. Such overlap may introduce interference between these segments that is not tolerable in an opto-acoustic system.

Another type of delay line extended the single layer polygonal disc into a three dimensional structure. This type of structure allows longer signals to be stored or processed. However, some aberration is introduced in the process of transferring the signal of one layer to the next layer of the polygonal delay line. For an example of this type of device, see U.S. Pat. No. 3,025,479 issued to John M. Wolfskill.

Another type of delay line which allows for differential delay in the transmission time is disclosed in U.S. Pat. No. 3,227,970 issued to Walter M. Andersen. Andersen shows a delay line in which a movable member which includes refracting surfaces is mounted on top of the delay line. Such a delay line, however, is not made of one integral solid piece, but requires precise mounting of the movable member and also precise alignment so that the signal is properly transmitted through the delay line. Neither can Andersen's teaching be extended to encompass a three-dimensionally folded delay line. Further, the laminated type construction of the Andersen device has the potential for introducing discontinuities which are not tolerable in an opto-acoustic system.

Another delay line using a liquid medium for transmission of compression waves is disclosed in U.S. Pat. No. 2,505,364 issued to H. J. McSkimin. McSkimin shows a system wherein the compression waves are transmitted through a series of parallel branches containing liquid mercury, folded from one to the next adjacent branch by a series of reflections from surfaces set at 45° to the direction of propagation. However, in such a liquid system distortion is difficult to control, i.e., mode conversion is a problem even though not introduced necessarily by the reflections the wave undergoes. Such a system could not be used in an optical system since it is not transparent to light and further is not conductive to conduction of shear waves.

SUMMARY OF THE INVENTION

The subject invention is directed to an acoustic delay line or processor for processing and transmitting acoustic signals preferably in an opto-acoustic system and comprises a solid integral body of acoustic signal conducting material which includes at least one planar path for carrying the acoustic signal in a folded non-

overlapping path, an input transducer connected to the integral body and an absorber connected to the solid integral body to prevent reflection of the signal back into the line. The folded path is accomplished without mode conversion by a selective choice of alignment angles of the reflective facets included in the body of the delay line.

BRIEF DESCRIPTION OF THE DRAWINGS

10 FIGS. 1a and 1b are block diagrams of representative opto-acoustic systems for processing acoustic signals incorporating the subject invention;

15 FIG. 2 is a projection view of one embodiment of the subject invention used as an opto-acoustic correlator or processor;

20 FIG. 3 is a plan view of the embodiment of FIG. 2 showing the partial paths of an acoustic signal and a replica signal; and

25 FIG. 4 is a projection view of another embodiment of the invention.

DETAILED DESCRIPTION OF THE INVENTION

In order to understand the operational environment of the subject invention, it is helpful to refer to the block diagram shown in FIG. 1a, wherein reference numeral 2 represents the folded path acoustic device which is the subject of the present invention, being utilized in an opto-acoustic system for processing of acoustic signals. The block diagram shown in FIG. 1b, 30 wherein reference numeral 12 represents a folded path acoustic device which is a second embodiment of the present invention, is another opto-acoustic system in which the subject invention can be used.

35 Referring to FIG. 1a, a laser beam 3 is incident normally (or at the Bragg angle) upon the face of acoustic delay line 2. An R.F. signal is injected at transducer 4 to the delay line 2 and, as will be pointed out in greater detail, the signal is folded in a path perpendicular to the incident laser beam. This opto-acoustic device relies on 40 the phenomena associated with the Debye-Sears effect or with the Bragg effect for diffraction of light; that is, that a collimated laser beam is diffracted by an acoustic signal of carrier frequency f into an angle $\phi = \lambda f / v_s$ while the frequency of the diffracted light is shifted 45 from that of the original beam by the amount of the acoustic frequency. In the above expression the light wavelength is λ , the acoustic velocity is v_s and the frequency of the acoustic signal is f . In the simple systems as shown in FIGS. 1a and 1b, the diffracted light intensity is directly detected by a photo-detector 10 after 50 passing through lens 8. The photo-detector 10, located in the Fourier transform plane or photo-detection plane, is connected to appropriate processing circuitry for processing of the information obtained from the acoustic signal. Such circuitry does not form any part of the subject invention.

55 FIG. 1a utilizes acoustic device 2 which has mounted thereon transducer 6 for injection of a reference signal to be compared to the RF signal which is injected to the acoustic device 2 by transducer 4. The system of FIG. 1b obtains similar results but instead of a reference signal being introduced into the acoustic device 12, a transparency 18 containing the spatial frequency of an acoustic wave is placed parallel and adjacent to the delay line.

60 The opto-acoustic device 20 shown in FIG. 2 represents one embodiment of the subject invention con-

structed from a solid integral piece of acoustic signal conducting material such as fused quartz in which the acoustic wave is transmitted in a two dimensional path. This correlator or processor takes advantage of the principle that no mode conversion takes place for a shear wave incident at 45° to a reflecting surface, with the shear polarization in the plane of incidence. This principle is well known in the art as discussed by R. N. Thurston in *Physical Acoustics*, W. P. Mason, Editor (Academic Press, New York, 1964) Volume I, pages 81-84. Thus, the shear wave transmitted through acoustic delay line 20 is reflected at each and every facet so that the angle of incidence is always 45°, thereby preventing mode conversion. This shear polarization direction is also that for which light incident normal to the plane of the delay line is most efficiently diffracted.

The opto-acoustic correlator or processor shown in FIG. 2 includes transducers 22 and 24 for injecting an RF signal and a replica signal respectively into device 20. Absorbers 25 and 23 prevent the reflection of the respective signals back into the device 20. It will be understood from the discussion above of FIG. 1b that transducer 24 and absorber 23 can be eliminated for certain applications. The absorber 25 can also be eliminated if reflection of the acoustic wave back into the opto-acoustic device 20 is not critical to the particular signal processing application. If the device 20 is used as a delay line, an output transducer would replace absorber 25.

The device 20 shown in FIG. 2 has parallel planar surfaces 29 and 27. Reflective side surfaces 31 and 33 are oppositely displaced from one another and have serrations formed thereon characterized by peaks and valleys parallel to the planar surfaces 29 and 27.

Looking now at FIG. 3 a more detailed description of the opto-acoustic device 20 is given below. An RF signal is introduced to delay line 20 by means of transducer 22. The signal follows a planar path 26. The signal is initially reflected from facet 28-1 which is inclined 45° to the path of the signal. The signal undergoes a second reflection at facet 28-2 which also is inclined at 45° to the direction of propagation of the signal. The double reflection of the signal from facets 28-1 and 28-2 causes the signal to reverse direction by 180° following branch 32-2. The signal in effect is folded from branch 32-1 to branch 32-2 by means of reflecting surfaces 28-1 and 28-2. Branches 32-1 and 32-2 are parallel and coplanar. This folding action is repeated at facet 30-1 and 30-2, causing the signal to fold back to branch 32-3 which parallels branches 32-1 and 32-2. The shear wave will continue to traverse the path 26 of delay line 20 along a multiplicity of parallel branches 32-1, 32-2, etc. being folded at facets 28-1 and 28-2, 30-1 and 30-2, 28-3 and 28-4, etc.

The segments of the path 26 which are vertical to the longitudinal branches 32-1, 32-2, 32-3, etc. identified by symbols 34-1 and 34-2 typically account for about 6 percent of the total path of the signal. Because of the vertical segments of the path, when the device is used in an opto-acoustic system, photo-detectors in the focal plane must provide for diffraction in both the horizontal and vertical directions, unless the vertical segments of the signal may be discarded.

A replica or reference signal can be introduced at transducer 24 and transmitted through delay line 20 along a folded path 36, as shown in FIG. 3. Planar path

36 is identical to planar path 26 except for traversing the delay line 20 in the opposite direction. Path 36 can be parallel and spaced apart from path 26 as shown in FIG. 2, or it can be coextensive with path 26 and not spaced apart. Such oppositely moving acoustic signals produce a correlation signal which, for example, can be acted upon by an incident laser beam.

An opto-acoustic correlator or delay line as shown in FIG. 2 could, for instance, have a total acoustic path length of about 82 centimeters when fabricated from an initial blank 7.6 centimeters square. Such a design which folds the acoustic wave into substantially a square format allows the device to be incorporated in an opto-acoustic system using round rather than cylindrical optics, and thereby requiring a much smaller aperture for processing the same amount of information than if the acoustic path length had not been folded. In this type of opto-acoustic correlator only shear waves polarized in the plane of incidence may be used to avoid mode conversion upon reflection and to provide for high light diffraction efficiency.

The folded path acoustic delay line shown in FIG. 2 can be extended into three dimensions. The extension into three dimensions is achieved by noting that the condition of no mode conversion upon reflection may also be satisfied for a configuration of incidence in which the shear polarization direction is parallel to the surface. These conditions are satisfied by the folded path acoustic delay line shown in FIG. 4. The device 50 of FIG. 4 has parallel planar surfaces 51 and 53. Side surfaces 55 and 59 are oppositely displaced one from another and each surface has two sets of serrations. Looking at side surface 55 it is seen that one set of serrations is characterized by reflective facets 56-1 to 56-6 and the second set of serrations is characterized by reflecting surfaces 62-1 to 62-8. The peaks and valleys defined by reflective facets 56-1 to 56-6 lie parallel to the planar surfaces 51 and 53. The peaks and valleys defined by reflective surfaces 62-1 to 62-8 lie normal to the planar surfaces 51 and 53.

The input signal is projected into the delay line 50 by means of input transducer 52. The shear wave follows folded path 54. It is reflected from facets 56-1 through 56-6 and 57-1 through 57-6 of the delay line 50, each of which is inclined 45° to the direction of propagation of the acoustic signal. The shear wave follows the path 54 which is comprised of a series of parallel branches 58-1 through 58-7 and segments 60-1 through 60-6 which are perpendicular to branches 58-1 through 58-7. The shear wave traverses the folded path 54 with its polarization in the plane of incidence, and incident at 45° to the reflecting surfaces at all times. After the shear wave traverses the last branch 58-7 of the planar path 54, the shear wave undergoes two reflections with polarization parallel to the reflecting surfaces 62-1 and 62-2. In this manner the shear wave is folded into a second planar path parallel to the first. This process may be repeated for as many planar paths as are provided in the particular delay line. An obvious result of this method of folding the acoustic wave is that no branch in the path overlaps any other branch. Since the branches of the path do not overlap, intra signal interference is avoided. A second transducer 64 may be used either to extract the acoustic signal from the delay line, or to project a replica in when using the device as an opto-acoustic correlator.

It should be understood that the parallel branches of each planar path as shown in FIG. 4 can be increased by utilizing a larger piece of acoustic signal conducting material having a corresponding larger number of reflecting facets 56. The number of parallel planar paths also may be increased by utilizing a piece of acoustic signal conducting material having a larger number of reflecting surfaces 62, the number being limited only by possible interference between adjacent branches when spaced too closely together.

A typical relationship between the length of the parallel branches 58 and the segments 60 which are perpendicular to branches 58 is 10 to 1. Thus, in such a configuration, approximately 10 percent of the total path is vertical to the major part of the path. However, this dimension can obviously be varied depending upon the application and the particular type of optical processing involved.

This opto-acoustic device allows for the folding of the path of an acoustic signal in three dimensions which is free of mode conversion for all reflections. The manner in which the acoustic path is folded in three dimensions is particularly suitable for opto-acoustic signal processing because each branch is isolated from all other branches. For such signal processing, the device of our invention might more specifically be described as an opto-acoustic correlator or processor. It is therefore to be understood that the terms correlator or processor along with delay line are within the meaning of the opto-acoustic device described in this specification.

What is claimed is:

1. A folded path acoustic device for processing acoustic wave signals, comprising:

a homogeneous solid integral body of acoustic signal 35 conducting material,

said body having a planar path for conducting said acoustic wave signal including a plurality of parallel branches terminated by reflective facets adapted to fold said acoustic wave signal from one of said branches to the next adjacent of said branches so that said signal remains in phase from branch to branch in a non-overlapping path, and first transducer means connected in a signal transfer- 40

ral relationship with said body for input of said acoustic wave signal into a selected branch of said acoustic device.

2. The acoustic device as set forth in claim 1 wherein said device further includes means connected in a signal transferral relationship with said body for receiving said acoustic signal.

3. The acoustic device as set forth in claim 2 wherein said means includes an absorber adapted to prevent reflection of said acoustic wave signal back into said acoustic device.

4. The acoustic device as set forth in claim 2 wherein said means includes an output transducer whereby said device can be used as an acoustic delay line.

5. The acoustic device as set forth in claim 1 wherein said transducer means is a shear-wave transducer connected to a selected one of said branches of said planar path adapted to polarize said acoustic wave signal in the plane of incidence of said acoustic wave with said reflective facets of said selected branch.

6. The acoustic device as set forth in claim 5 wherein said reflective facets are aligned at 45° to the direction of propagation of said acoustic signal.

7. The acoustic device as set forth in claim 6 wherein said homogeneous solid body includes said planar path having a number of said parallel branches such that said planar path assumes substantially a square format in the plane of said planar path whereby round optics can be used to process optical signals transmitted through said solid body by means of said acoustic signal.

8. The acoustic device as set forth in claim 6 which 10 further includes a second planar path for conducting a replica acoustic signal having a plurality of parallel branches and second transducer means connected in a signal transferral relationship with a selected one of said branches of said second planar path for input of 15 said replica acoustic signal to said selected branch of said second planar path.

9. The acoustic device as set forth in claim 8 wherein said second planar path is coextensive with said first planar path.

10. A folded path acoustic device for processing an acoustic wave signal comprising:

a homogeneous solid integral body of acoustic signal 20 conducting material;

first transducer means connected in a signal transfer- 25

ral relationship with said body for input of said acoustic wave signal to said acoustic device; 30

said body having a plurality of parallel planar paths 35

for carrying said acoustic wave signal, each of said planar paths including a plurality of parallel branches terminating in reflective facets adapted to fold without mode conversion said acoustic wave signal from one of said branches to the next adjacent of said branches so that said acoustic wave signal is passed in a non-overlapping path in phase from branch to branch,

said planar paths further including reflective means

adapted to fold said acoustic wave signal from one

of said planar paths to a next adjacent one of said

planar paths whereby said acoustic wave signal is

passed in a non-overlapping path from planar path

to planar path; and

means connected in a signal transferral relationship

with said body such that said acoustic wave signal

is not reflected back into said delay line.

11. The acoustic device as set forth in claim 10 wherein said means include an absorber adapted to prevent reflection of said acoustic wave signal back into said acoustic device.

12. The acoustic device as set forth in claim 10 wherein said means include an output transducer whereby said device can be used as an acoustic delay line.

13. The acoustic device as set forth in claim 10 wherein said first transducer means is a shear-wave transducer adapted to polarize said acoustic signal in a plane of incidence of said acoustic wave signal with said reflective facets of said branches.

14. The acoustic device as set forth in claim 13 wherein said reflective facets are at 45° to the direction of propagation of said acoustic wave signal.

15. The acoustic device as set forth in claim 14 wherein said reflective means includes two reflective surfaces at 90° to each other and 45° to the direction of propagation of said acoustic wave signal for folding said acoustic signal from one planar path to a next adjacent planar path whereby said acoustic signal does not undergo mode conversion.

16. A homogeneous solid integral body of acoustic signal conducting material comprising:
a first planar surface,
a second planar surface parallel to and spaced apart from said first planar surface,
first and second oppositely displaced side surfaces each having a first set of serrations having peaks

and valleys so arranged and constructed that said peaks and valleys are parallel to said first and second planar surfaces and a second set of serrations having peaks and valleys so arranged and constructed that said peaks and valleys are normal to said first and second planar surfaces.
